UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR CARS.

1,273,908.

Specification of Letters Patent. Patented July 30, 1918.

Application filed November 23, 1916. Serial No. 132,957.

To all whom it may concern:

Be it known that I, JOHN F. O'CONNOR, a citizen of the United States, residing at Chicago, in the county of Cook and State of Illinois, have invented a certain new and useful Improvement in Draft-Riggings for Cars, of which the following is a full, clear, concise, and exact description, reference being had to the accompanying drawings, 10 forming a part of this specification.

This invention relates to improvements in draft riggings for cars.

The object of the invention is to provide simple and effective means on a follower of 15 a draft rigging for limiting the movements of the draw bar and so arranged as to distribute the ultimate loads to the draft sills at widely separated points.

In the drawing forming a part of this 20 specification, Figure 1 is a part top plan, part horizontal section of a draft rigging embodying my improvements. Fig. 2 is a view similar to Fig. 1 illustrating a different embodiment of my invention. Fig. 3 is a 25 perspective view of the novel follower employed with the construction illustrated in Fig. 1. Fig. 4 is a perspective view of the front follower employed with the construction illustrated in Fig. 2. And Fig. 5 is a 30 vertical, sectional view taken substantially on the line 5—5 of Fig. 2 to illustrate the draw bar and yoke connection.

Referring to the construction illustrated in Figs. 1 and 3, 10—10 denote center sills 35 to which are secured rear stops 11—11 and front plate stops 12—12, each of the latter having a rear vertical shoulder 13 and a front vertical shoulder 14. 15 designates a combined friction shell and spring casing 40 of a well known form with which co-operates friction elements 16, the gear being connected to the draw bar 17 by a yoke strap 18.

Co-operable with the gear is a front follower designated generally by the reference 45 A. Said follower A comprises a transversely extending portion 19 with rearwardly extended side walls 20 on each side thereof and forwardly extended side walls 21. The rearward extensions 20 are each 50 provided with outwardly extended shoulders 22 which normally engage said shoulders 13 and the forward extensions 21 are each provided with an outwardly extended shoulder 23 normally spaced from the stop 55 shoulders 14 a distance corresponding to the

permissible movement of the gear. For strength, the follower A is provided with upper and lower flanges 24 and 25 arranged as most clearly shown in Fig. 3.

The normal position of the parts is illustrated in Fig. 1. Upon buff or inward movement of the draw bar, it is apparent that the follower A will be moved rearwardly thus actuating the friction elements, which movement continues until the shoulders 23 engage the shoulders 14, the front follower A thus acting as a limiting stop. Under draft, the follower A is held stationary by the engagement of the shoulders 22 with the shoulders 13, the gear being actuated in the usual manner against the follower.

In the construction illustrated in Figs. 2, 4 and 5, the arrangement of sills, rear stops, front stops and gear is the same as for the 75 construction illustrated in the other figures. In this construction, however, a different type of front follower is employed, the same being designated generally by the reference B. Said follower B comprises a transversely extending portion 119 and forwardly extended side arms 121, each of the latter being provided with outwardly extending shoulders 123 adapted, under full buff, to engage the front shoulders 114 of the front 80 stop members. In this construction, the follower B is prevented from forward movement by a stationary key 30 which extends through corresponding slots in the sills and an elongated slot 31 in the draw 85 bar 117. The side extensions 121 of the follower are also slotted as indicated at 32 to accommodate the key 30, as appears from Fig. 2. The slots 31 are elongated so as to 90 permit either forward or rearward movement of the draw bar with respect to the key 30 and in order to effect the connection of the yoke 118 with the draw bar, the rear end of the latter is left open as indicated at 33 so that short rivets 34 may be 95 employed to connect the ends of the yoke strap.

In operation, the follower B remains stationary under draft, being held by the key 30. In buff, the draw bar engages the follower B and forces the same rearwardly thus actuating the gear until the shoulders 123 engage the shoulders 114, the follower thus 100 acting as a limiting stop under buff.

It will be noted that in each of the co- 110

structions above described, the front follower is so designed as to provide a pocket for the reception of the butt of the draw bar, or stated in another manner, the front follower is provided with forward extensions overlapping the sides of the draw bar butt. With this arrangement the loads transmitted to the sills through the follower under buff are applied well forward of the rear stops of the rigging, thus distributing the shocks to the sills at widely separated points.

I claim:

1. In a draft rigging, the combination with draft sills having main front stops thereon, of cushioning means, a front follower, and integral means on said follower coöperable with said stops to limit the rearward movement of the follower.

2. In a draft rigging, the combination

with draft sills having front stop members secured thereto, of cushioning means, a draw bar, a yoke, and a front follower, said follower having forwardly extended side arms, the latter having shoulders adapted to coöperate with said stop members to limit the inward movement of the follower. 25

3. As an article of manufacture, a follower for draft riggings having a transversely extending portion and forwardly extended side arms, the latter forming a pocket to receive the butt of a draw bar, said side arms being provided with laterally extending shoulders adapted to coöperate with fixed members to limit the inward movement 30 of the follower. 35

In witness that I claim the foregoing I have hereunto subscribed my name this 16th day of Nov., 1916.

JOHN F. O'CONNOR.
